UNITED STATES PATENT OFFICE.

JOHN A. TOPPING, OF CHICAGO, ILLINOIS.

PREFORMED ROADWAY-BLOCK.

1,150,558.

Specification of Letters Patent. Patented Aug. 17, 1915.

Application filed October 5, 1914. Serial No. 865,096.

To all whom it may concern:

Be it known that I, JOHN A. TOPPING, a citizen of the United States, residing at Chicago, in the county of Cook and State 5 of Illinois, have invented certain new and useful Improvements in Preformed Roadway-Blocks, of which the following is a specification.

My invention relates to improvements in 10 building constructions and has especial reference to the preparation and application of asphalt mastic, or the like, for this purpose.

One of the objects of my invention is to 15 incorporate in sheets, mats or relatively small blocks of asphalt mastic a restraining and weight bearing structure, whereby to prevent the mastic from wrinkling and creasing when applied in sheets to roadways 20 and floors and to prevent it from sagging when applied to walls, more or less vertical, as side walls of rooms, roofs, and the like, and which structure will receive and sustain the greater portion of the burden of 25 a concentrated vertical load incident to its use in roadways, walks, floors, waterproofing for bridges, viaducts, etc.

Another object of my invention is to pre- 30 form relatively thin sheets, blocks or mats of mastic asphalt, with the weight bearing structure therein, of uniform size and character, at a factory, said blocks being so constructed and arranged as to provide and preserve a uniform structure throughout 35 after being placed in position on a roadway, or the like, the interlapping parts of the metal portions being such as to produce the same disposition of metal at the lines of jointure as obtain throughout the body part 40 of the block.

Other and further objects of my invention will become readily apparent to persons skilled in the art from a consideration of the following description, when taken in 45 conjunction with the drawings, wherein:—

Figure 1 is a plan view of the finished block or mat showing parts of the restraining, metal structure within. Fig. 2 is a fragmental view showing how adjacent 50 blocks are joined at proximate edges when the construction is laid in a plurality of relatively small blocks instead of larger single sheets. Fig. 3 is a section taken on line 3—3 of Fig. 1. Fig. 4 is an isometric perspective view of the metallic restraining 55 structure. Fig. 5 is a section taken on line 5—5 of Fig. 2.

In all the views the same reference characters are employed to indicate similar parts.

A roadway or floor, made of asphalt mastic, or having a covering coating of asphalt mastic, possesses many admirable and advantageous features, it also has certain recognized faults. Under temperature of 57 65 degrees Fahrenheit a sheet of unsupported asphalt mastic three-quarters of an inch thick will carry a vertically applied super- 70 posed load of 1000 pounds, in an ordinary wagon, without producing appreciable indentation by the wheels. Under a temperature of 98 degrees Fahrenheit, however, the asphalt coating is much softer and will readily yield to a similarly concentrated load of the same weight. Under the conditions 75 mentioned the mastic is not compacted but is caused to creep or crawl from under the wheels. Such action is known in the art as "shoving", and when the load is withdrawn the depressions thus made are left in the 80 soft mastic. The mastic is not mobile enough to come back to its original position and under the effect of constant traveling over the same surface, deep depressions or ruts will thus be made in the asphalt.

The object of my invention is to eliminate such objectionable features, by incorporating in the sheet of mastic, a metal fabric made up of a series of wide, relatively thin strips crossing each other at 90 suitable angles and placed upon their edges so as to have their greatest dimensions in vertical planes, and providing pockets between said strips, which are to be filled with asphalt mastic until the said mastic is sub- 95 stantially flush with the longitudinal, relatively thin edges of said strips. When such a metallic restraining structure is incorporated in a sheet of asphalt mastic, as described, the mastic is held and restrained 100 against shoving, or lateral displacement, by the side walls of the pockets so that it cannot move out to any great extent from under the surface of the vehicle wheels, and the pressure applied to the mastic proper, 105 in the new construction, is not as great because the incorporated metal fabric will take the load, or most of it. The only stress

or strain that is applied to the asphalt in road way or floor constructions is that of compression, and therefore my incorporated restraining fabric prevents the spreading 5 or "shoving" of the asphalt and receives and sustains the weight of the load upon its vertical edges. To support the metal fabric within the asphalt mat, I laterally deflect a longitudinal portion of the strip 10 to form a base thereby giving a greater weight bearing surface to the fabric in contact with the underlying base.

My incorporated restraining structure in a sheet of relatively thin block of asphalt is 15 not in the nature of a reinforcement, to increase the tensile strength or to resist the pulling apart of the mastic material associated therewith, as similar structures are used in cement blocks. In using asphalt 20 mastic in connection with floor and roadway structures the tensile strength of the material is not called into requisition.

I have herein shown one exemplification for carrying my invention into effect and in 25 Fig. 1 I have shown how a structure may be made in relatively small blocks or mats of suitable size and subsequently put together at the place, floor, or roadway, where they are to be used. Relatively long strips 10 alternate with relatively shorter parallel strips 10' and cross strips 11, which are 30 longer than the intermediate strips 11' cross the strips 10 and 10'. A portion of each of the strips is deflected, as at 12, to form a base for 35 support of the vertical portion 13. The vertical wall 13 is notched at intervals, as at 14, within which to receive the adjacent cross strip. A portion of the vertical wall 13 is down turned, as at 15, to provide a base upon 40 which the cross strip may rest. The down turned portion 15 may be riveted, or spot welded to the superposed cross strip, as at 45 16, to hold the strips together to form pockets in which to receive the mastic material 17. The mastic material 17 is placed 50 in the pockets, provided in the restraining metal fabric, compressed and compacted therein until it entirely fills the pockets and 55 is flush with the vertical edges on each side 60 of the metal fabric. In Fig. 1 it will be observed, that the longer bars or strips project beyond the pockets near the outer boundary of the block formed by the mastic material. These bars or strips are arranged with reference 65 to the adjacent blocks or sheets, as shown in Fig. 2, wherein alternate elongated bars are placed adjacent the shorter bars of the next block, or sheet and mastic material 17' is filled in the pockets thus provided at the joints after the mats or sheets have been placed in position and fixed on the underlying base or roadway and by this means pockets of uniform size and shape are evenly distributed throughout the entire 70 structure of asphalt mastic.

If a sheet, substantially as shown in Fig. 1, be applied to a vertical wall, or to a roof, the walls 13, of the structure, will support the mastic contained in the respective pockets and prevent "shoving," falling or sagging. The mastic placed in one pocket, in 75 the structure, communicates with that in another pocket through the gaps, or notches 14 provided by the down-turned joint portions 15 of the crossing strip, and by this 75 means there is a knitting together of the mastic within each and every one of the pockets in the entire mat or sheet.

I realize that mastic asphalt or composition may be made sufficiently strong or 80 staunch and less yielding, to withstand any ordinary load that may be imposed upon it, by the admixture of cement, sand or other like comminuted similar substances when otherwise the mastic materials would be too 85 soft without these admixtures, as in summer weather when the temperature is from 90 to 100 degrees. But such admixtures for making the composition of such a character as to withstand the conditions to which it is 90 subjected under such temperature, when subjected to cold weather, as when the temperature is down below the freezing point, readily cause such mastic composition to 95 crack and break thereby destroying the usefulness of the roadway.

By the use of my invention all of the desirable qualities of the yielding mastic asphaltic materials may be availed for the purpose, providing a structure that will stand 100 the rigors of the coldest climate without cracking or disintegrating and capable of carrying the heaviest loads to which it would be subjected during summer weather of higher temperature.

While I have herein shown a single embodiment of my invention for the purpose of clear disclosure, it is manifest that considerable change in the arrangement and disposition of the parts may be made within 105 the scope of the appended claims without departing from the spirit thereof.

Having described my invention, what I claim is:—

1. A building structure comprising a metallic fabric consisting of a series of parallel L-shaped metal strips; a second series of parallel L-shaped metal strips crossing the first series of strips, the under strip in each instance having portions of its vertical wall 115 down turned into a plane with its base wall; means to secure said down turned portions of the lower strips to the bases of the superposed strips, and a filling of homogeneous material flush with the top and bottom edges 120 of said strips.

2. A building structure comprising a metallic fabric consisting of a series of parallel L-shaped metal strips; each strip consisting 125 of a base wall and a vertical wall; a second

series of parallel L-shaped metal strips, crossing the first series of strips, the under strip in each instance having portions of its vertical wall at the crossing downturned into 5 a plane with its base wall and a filling of homogeneous material flush with the top and bottom edges of said strips.

In testimony whereof I hereunto set my hand in the presence of two subscribing witnesses.

JOHN A. TOPPING.

In the presence of—

STANLEY W. COOK,

MARY F. ALLEN.
